(57) **CLAIM**

The ornamental design for the box, as shown and described.

DESCRIPTION

FIG. 1 is a perspective view of a box, showing my new design in an open state;

FIG. 2 is a front elevation view thereof;

FIG. 3 is a rear elevation view thereof;

FIG. 4 is a right-side elevation view thereof;

FIG. 5 is a left side elevation view thereof;

FIG. 6 is a top plan view thereof;

FIG. 7 is a bottom plan view thereof;

FIG. 8 is a perspective view thereof, in condition of use;

FIG. 9 is a front elevation view thereof;

FIG. 10 is a perspective view of the box, in a closed state;

FIG. 11 is a front elevation view thereof;

FIG. 12 is a rear elevation view thereof;

FIG. 13 is a right-side elevation view thereof;

FIG. 14 is a left-side elevation view thereof;

FIG. 15 is a top plan view thereof; and,

FIG. 16 is a bottom plan view thereof.

The broken lines in FIGS. 8 and 9 are for environmental structure only and form no part of the claimed design.

1 Claim, 12 Drawing Sheets
